[57] CLAIM

The ornamental design for a computer mouse, as shown and described.

DESCRIPTION

FIG. 1 is a top front and left side perspective view of a computer mouse showing our new design;

FIG. 2 is a top view thereof;

FIG. 3 is a left side view thereof;

FIG. 4 is a front view thereof;

FIG. 5 is a right side view thereof;

FIG. 6 is a rear view thereof;

FIG. 7 is a bottom view thereof; and

FIG. 8 is a bottom view of a second embodiment thereof the sole difference being the golf ball-like dimpled shape of the roller ball.

The cord is shown broken away in the views to indicate an indetermined length.
